VISIBLE CARD INDEX

James R. Clark, Rochester, N. Y., assignor to The
Yawman & Erbe Manufacturing Company,
Rochester, N. Y., a corporation of New York

Application November 1, 1938, Serial No. 238,155

12 Claims. (Cl. 129—16)

This invention relates to visible card indexes. More specifically, the invention relates to an improved visible index in which the hinge elements of index cards are inserted in slots perforated in flexible holders which may be sprung into suitable grooves in an index tray. An important feature of the invention is that it provides a visible index wherein the index cards may be readily inserted in the slots in the card holders, and in which means is provided to prevent lateral displacement of the hinges in the slots after insertion therein.

An object of this invention is to provide a visible index in which cards may be inserted without first being bowed to reduce the distance between the hinges formed thereon.

Another object of the invention is to provide an index of the above character in which the cards may be releasably locked in position, so that the hinges cannot be inadvertently moved laterally in the slots.

A further object of the invention is to provide an index of the above character wherein the cards may be held in an offset position in which they may also be locked releasably against inadvertent lateral displacement.

In the preferred embodiment of the invention a plurality of ribs are provided in the bottom of the tray which serve to space the holders from the bottom thereof. These ribs support the holders in the proper position and at the same time they provide sufficient space between each holder and the bottom of the tray for the insertion of the card hinges into the slots. The holders are preferably made of a flexible light material, so that they may be bowed to reduce their length for insertion in suitable grooves formed in the sides of the tray.

Two or more spaced slots are perforated in the holders, each of which is provided with a wide portion and a restricted portion. The restricted portion is preferably as long as the wide portion, although, obviously, it may be made longer or shorter if desired. The distance between the wide portions of the slots in any holder is made the same as the distance between the hinges on the card or cards to be supported, so that the hinges may be inserted in the wide portion of the slots without the necessity of bowing the card. This last feature results in a substantial increase in the useful life of the cards, since it has been found that in constructions where the cards must be bowed after frequent insertions and removals, a crease forms in the central portion of the cards which weakens them.

to such an extent that their usefulness is much reduced and frequent replacements are necessary.

The advantages of this invention are due in part to the relationship existing between the ribs in the bottom of the tray and the slots in the card holders. The ribs, preferably, but not necessarily, equal in number to the number of slots in the holders or card hinges to be engaged, extend longitudinally of the tray and project upwardly to the lower face of each holder. These ribs are spaced in the bottom of the tray in such relation to the slots in the holders that the card hinges may be freely received in the wide portions of the slots, and may be releasably held in the narrow portions thereof, so that inadvertent lateral displacement of the hinges in the slots may be effectively prevented.

Additional objects of the invention will be apparent from the following detailed description taken in connection with the accompanying drawing, in which:

Figure 1 is a partial view in plan of a visible index constructed in accordance with this invention;

Figure 2 is a view in section taken through the line 2—2 of Figure 1, looking in the direction of the arrows, showing several cards assembled in the tray in the locked position;

Figure 3 is a view in section taken along the line 3—3 of Figure 1, illustrating a card in an offset position;

Figure 4 is a partial view in section illustrating the manner in which the hinges may be inserted in the slots; and

Figure 5 is a partial view in section of a modification of Figure 3 illustrating the manner in which the cards may be frictionally held in the offset position.

Referring to Figures 1 and 2, the tray of a visible index is shown at 10 which comprises a bottom plate 11 in which the channels 12 and 13 are formed. These three channels extend for the entire length of the tray 10, channel 12 being disposed in the central portion of the tray while channels 13 are formed adjacent its two sides. Secured to the two sides of the plate 11 are two channel members 14, on each of which a flange 15 is formed which lies parallel to the upper surface of the channel 13, forming a narrow groove 16 therebetween in which the flexible holders 17 are adapted to be received.

The holders 17 are formed with a plurality of slots 18 and 19 which are provided with restricted portions 20 and 21 extending longitudi-

nally in the same direction along the holders 17, the restricted portions 21 being about twice as long as the restricted portions 20.

To the bottom of the plate 11 are secured a plurality of ribs 22, which extend for the length of the tray, having raised portions 23 which extend to the lower surface of the holders 17.

The index cards 25 may be rectangular in shape, as shown in Figure 1, or half-size cards 26 may be used if it is desired to have two of these cards in one card holder. The cards have secured thereon the hinges 24 which may be formed of a strip of fabric which is bent back on itself to form two leaves with a pintle on the folded edge, which are secured by means of a suitable adhesive to the front and rear faces of the card.

In assembling the visible index, the flexible holders 17 are first bowed to reduce the length between their ends so that the ends may be inserted into the narrow recesses 16. The holders 17 are then allowed to return to the normal flat position in which they rest on the supporting channels 12 and 13 in such fashion that they are spaced at all points by a predetermined amount from the bottom of the tray. The hinges 24 on the card 25 are first inserted in the wide portions of the slots 19 and the card is then moved laterally to the right until the hinges 24 engage the entrance to the restricted portions 21, and the pintles of the hinges are below the lower face of the holder. As shown in Figure 4, further lateral movement of the left hinge 24 is prevented by the raised portion 23 of the rib 22 at the extreme left hand side of the tray, so that the card must be raised upwardly in order to bow the holder 17 by an amount sufficient to permit hinge 24 to pass over the raised portion 23. The hinge 24 may now be moved laterally to the right in the restricted portion 21 when the card 25 may be released and the holder 17 restored to its normal position on the channels 12 and 13.

As illustrated in Figure 2, the hinges 24 on the card 25 are placed so that they may be inserted in the two innermost slots 18 and then moved to the locked position. It will be noted that the effective length of the restricted portion of the slot 20 is but slightly larger than the width of the hinge 24, so that lateral motion thereof is almost entirely prevented. Once the hinges 24 have been inserted and the cards are in the locked position, it is obvious that they cannot thereafter be inadvertently moved from the restricted portion of the slot.

If desired, two cards may be inserted in one holder as is shown in Figure 2, in which case hinges are provided on one card to engage the slots 18 while the hinges on a second card, shown in dotted lines, are adapted to be inserted in the slots 19. When the second card is inserted in the slots 19 it will be locked in position against movement to the left by the raised portion of the rib at the extreme left hand side of the tray, and against movement to the right by the raised portion of the rib at the extreme right hand side of the tray, from which position it cannot be removed without first lifting the card to bow the flexible holder 17.

An additional filing division may be obtained by offsetting some of the cards in the tray, as shown in Figure 3. This may be accomplished by lifting the card shown in dotted lines in Figure 2 so that its right-hand hinge may be moved past the raised portion 23 of the rib 22 at the extreme right-hand side of the tray into the position shown in Figure 3, in which the card will be locked in

the holder, and offset with respect to the tray. It will be noted that the rib 22 at the extreme right hand side of the tray serves to keep the hinge 24 from being inadvertently moved laterally so it will not slip out of the holder. It is evident that by offsetting part of the cards as shown in Figure 1, they may be divided into two groups in addition to the customary well known filing divisions.

As an alternative, cards may be frictionally held in the offset position as illustrated in Figure 5. This may be accomplished by moving the card to the right until the pintle of the hinge 24 rests upon the raised portion 23 of the rib 22, beneath the strip 17. The pressure exerted on the pintle of the hinge 24 by the under surface of strip 17 and the raised portion 23 of rib 22 gives rise to sufficient friction to hold the card effectively in the offset position.

Although the flexible holders 17 may be made of any flexible material, it is preferred that they be made of fibre which is extremely light and from which they may be economically and effectively manufactured. This material can be easily stamped so that it is possible to stamp out the completed holder, including the slots, in one operation. Furthermore, one great advantage in using fibre lies in the fact that it is extremely light and therefore does not add appreciably to the weight of the assembled tray. Fibre sticks of this character, moreover, may be very easily bowed prior to insertion in the tray without being damaged to any extent thereby, and since, in accordance with this invention, the strips are not continually flexed when assembled in the tray, they will retain their flexible properties over long periods of time.

The replacement of a card holder after removal may be facilitated by providing holders of different colors, as, for example, red and black, and arranging them in the tray in such fashion that adjacent holders are of different color. When one holder is removed, its position will be marked by the two adjacent holders which will be of the same color, so that to locate the position of the removed holder, one need only look for two adjacent holders which are of the same color.

The provision of holders of different colors further assists in the insertion of each card in its proper holder. Because of the proximity of the holders in the tray, it might be possible inadvertently to insert the left hinge in a slot of one holder and the right hinge in a slot of an adjacent holder, if the holders are all of the same color. Where adjacent holders are of different colors, however, this is impossible, since the proper holder is identified by a distinctive color, and it is spaced from the nearest holder of the same color by a holder of different color. Even when several adjacent holders are of the same color, the finding of the correct line of slots is facilitated by the narrow band of color, distinguishing this small group of holders.

Where it is not desired to use individual holders, a solid sheet of flexible material 27 may be used, as illustrated in Figure 1, which may be provided with series of slots running longitudinally in groups of two or more laterally, as, for example, the slots 28 and 29. Depending on the length and width of the flexible sheet, the thickness of the sheet may vary in order to permit it to flex when the hinge is inserted and moved laterally over the ribs in the bottom of the tray.

The tray in which the holders are received may be made out of sheet steel or some other similar

material in which the channels 12 and 13 may be stamped out in one operation. The ribs 22 are standard items, as are the channel members 14, so that they may be easily cut to the proper size and spot welded or otherwise secured in position, as shown in Figures 2 and 3. The entire tray, therefore, may be constructed and assembled with a minimum number of simple manufacturing operations, thus providing a sturdy and effective visible index which is at the same time inexpensive and easily manufactured.

It is evident that where the word "rib" is used throughout the specification, it is intended to include angles.

The invention provides an improved visible index which is light in weight, inexpensive and simple in construction. Furthermore, the novel tray construction including the channels beneath the slot portions in the card holders, and the locking ribs or angles formed, welded or otherwise secured in position, in the bottoms of the channels, enables the cards to be readily inserted in the holders in such fashion that they cannot be thereafter inadvertently moved laterally in the holders, thus providing a visible index of highly serviceable character.

While a specific embodiment of the invention has been described above, it is not intended to be in any way limited thereby except as defined in the appended claims.

I claim:

1. In a visible card index, the combination of a flexible card holder, a tray in which the card holder is adapted to be received, a plurality of longitudinally extending slots in the said card holder in which the hinges of a file card are adapted to be received, each slot having a wide portion and a narrow portion, the narrow portions of the slots extending in the same direction, means in the tray forming an open channel beneath each of the said slots, and means in the channels for locking the card hinges in the narrow portions of the slots.

2. In a visible card index, the combination of a card holder, a tray in which the card holder is adapted to be received, a plurality of longitudinally extending slots in the card holder in which the hinges of a file card are adapted to be received, each slot having a wide portion and a narrow portion, and the narrow portions of the slots extending in the same direction, means in the tray forming an open channel beneath each of the said slots, and at least one member in the tray having a raised portion extending upwardly to the under surface of the said card holder, whereby inadvertent lateral movement of the card hinges in the narrow portions of the slots is prevented.

3. In a visible card index, the combination of a card holder, a tray in which the card holder is adapted to be received, a plurality of longitudinally extending slots in the card holder in which the hinges of a file card are adapted to be received, each slot having a wide portion and a narrow portion, and the narrow portions of the slots extending in the same direction, means in the tray forming an open channel beneath each of the said slots, and at least one member in the tray having a raised portion extending upwardly to the under surface of the said card holder at a point below the narrow portion of a slot, whereby inadvertent lateral movement of the card hinges in the narrow portions of the slots is prevented.

4. In a visible card index, the combination of a file card having hinges thereon, a flexible card holder, a tray in which the card holder is adapted

to be received, a plurality of longitudinally extending spaced slots in the said card holder adapted to receive the hinges of the file card, each slot having a wide portion and a narrow portion,

5. The narrow portions of the slots extending in the same direction and being substantially twice as long as the width of a card hinge, means in the tray forming an open channel beneath each of the said slots, and at least one member in the tray having a raised portion extending upwardly to the under surface of the said card holder, whereby the card may be moved laterally to an offset position in the holder in which position it will be locked against inadvertent lateral movement.

10. 5. A visible card index comprising a flexible card holder, a plurality of longitudinally extending spaced slots in the said card holder adapted to receive the hinges of a file card, each slot having a wide portion and a narrow portion, a tray in which the said holder is adapted to be received, and a plurality of longitudinally extending ribs in the tray adapted to cooperate with the said slots for allowing the hinges to be freely received in the wide portions of the slots, and for holding the hinges releasably in the narrow portions of the slots.

15. 6. A visible card index comprising a flexible card holder, a plurality of longitudinally extending spaced slots in the said card holder adapted to receive the hinges of a file card, each slot having a wide portion and a narrow portion, the narrow portion being at least as long as the width of a card hinge, a tray in which the said holder is adapted to be received, and a plurality of longitudinally extending ribs in the tray, each of the said ribs having a raised portion extending substantially to the under face of the said holder, to a point beneath the narrow portion of a slot spaced from its closed end by a distance at least equal to the width of a card hinge, whereby the card hinges may be freely received in the wide portions of the slots, and releasably held in the narrow portions thereof.

20. 7. In a visible card index, the combination of a card holder, a tray in which the card holder is adapted to be received, a longitudinally disposed series of spaced slots in the card holder in which the hinges of file cards are adapted to be received, each of said slots extending laterally of the tray and having a wide portion and a narrow portion, and the narrow portions of the slots extending in the same direction, means in the tray forming an open channel beneath each of the said slots, and at least one member in the tray having a raised portion extending upwardly to the under surface of the said card holder, whereby inadvertent lateral movement of the card hinges in the narrow portions of the slots is prevented.

25. 8. In a visible card index, the combination of a supporting frame, a card holder in said frame, a plurality of longitudinally extending slots in the upper face of said card holder in which the hinges of a file card are adapted to be received, means in said frame for spacing said card holder from the bottom thereof, and means projecting upwardly from the frame and adapted to cooperate with the slots in said card holder for locking the card hinges releasably therein.

30. 9. In a visible card index, the combination of a supporting frame, a card holder in said frame, a plurality of longitudinally extending slots in said card holder in which the hinges of a file card are adapted to be received, each slot having a

wide portion and a narrow portion, the narrow portions of the slots extending in the same direction, means in the frame for spacing said card holder from the bottom thereof, and means in the frame, adapted to cooperate with said card holder for locking the card hinges in the narrow portions of the slots thereof.

10. A visible card index comprising a supporting frame, a card holder in said frame, a plurality of longitudinally extending slots in said card holder, adapted to receive the hinges of a file card, each slot having a wide portion and a narrow portion, a raised member in the supporting frame for spacing said card holder from the bottom thereof, and a plurality of longitudinally extending ribs in the frame, adapted to cooperate with said card holder for allowing the card hinges to be freely received in the wide portions of the slots therein, and for locking the hinges releasably in the narrow portions of the slots therein.

11. A visible card index comprising a supporting frame, a plurality of flexible card holders in said frame, each of said card holders having a plurality of longitudinally extending slots formed therein in which the hinges of a file card are adapted to be received, means in said frame forming a longitudinally extending inverted

channel adjacent opposite sides thereof, means cooperating with the said channels to form a pair of opposite grooves in which the ends of said card holders may be sprung, means in the central portion of the frame forming an inverted channel for supporting said card holders, and means in the frame, between said side channels and said central channel, adapted to cooperate with each of said card holders for locking the hinges of a card releasably in the slots therein.

12. A visible card index comprising a supporting frame, means at opposite sides of the frame forming a pair of opposite grooves, a plurality of flexible card holders sprung into said grooves, alternate holders being of different color whereby the replacement of a removed holder or card may be facilitated, a plurality of longitudinally extending slots in the upper face of each of said card holders in which the hinges of a file card are adapted to be inserted, means in the central portion of the frame forming an inverted channel for spacing the holders from the bottom thereof, and means projecting upwardly from the frame and adapted to cooperate with the slots in each of said card holders for locking the hinges of a card releasably therein.

JAMES R. CLARK.
